His Attorney.

UNITED STATES PATENT OFFICE.

LEONARD P. HUTT, OF SCHENECTADY, NEW YORK, ASSIGNOR TO GENERAL ELECTRIC COMPANY, A CORPORATION OF NEW YORK.

SWITCH CONSTRUCTION.

1,342,999.

Specification of Letters Patent. Patented June 8, 1920.

Application filed December 10, 1917. Serial No. 206,361.

To all whom it may concern:

Be it known that I, LEONARD P. HUTT, a subject of the King of Great Britain, residing at Schenectady, in the county of Schenectady, State of New York, have invented certain new and useful Improvements in Switch Construction, of which the following is a specification.

This invention relates to switch construction and has for its object an improved construction and arrangement of parts whereby the life of the switch contacts is materially increased.

More specifically this invention relates to electro-magnetically actuated switches or contactors designed for heavy duty such as where it is necessary to make and break large currents in rapid succession.

It has been proposed to accelerate the opening movement of contactors beyond that naturally afforded by gravity by applying additional force to the opening movement such as that obtained from a spring compressed by the closing movement, in order to dissipate the arc more quickly and consequently increase the life of the contactor. It was found desirable to have such additional acceleration applied not only during that portion of the opening movement in which the contact making members are in rolling contact or "wiping" on one another but also for an appreciable interval of time after the contacts have separated in order to secure the largest practical increase in the life of the contactor.

In accomplishing this increase in the life of contactors in accordance with the practice of the prior art to get the desired acceleration, it was necessary to increase the size of the spring and consequently to increase the size of the actuating electromagnetic winding, which increase was objectionable because it necessitated an increase in both the weight and size of the contactor and required more energy to operate it. The increase in weight was particularly objectionable because the added inertia of the moving parts created a tendency for the contact making members to stick or "freeze" to each other.

In carrying my invention into effect, I employ a double pole contactor ordinarily designed to break a circuit in two points simultaneously and so arrange one set of contact making members with respect to the

other, that one of the original springs will give the additional acceleration by being made to act for an appreciable time after the other set of contacts have opened thereby avoiding the necessity for increasing the size and weight of the contactor while accomplishing the desired increase in the life of the contactor.

For a more complete understanding of the nature and objects of this invention reference should be had to the following detailed description, taken in connection with the accompanying drawing in which Figure 1 is a side elevation of an electromagnetically actuated contactor embodying my invention, while Fig. 2 is a front elevation of such contactor and Fig. 3 is a view indicating in diagrammatic fashion the arrangement of the contacts in a power circuit.

Referring now to the drawing, 5 denotes a back of insulating material on which is mounted a magnetic frame 6 carrying an electromagnetic winding 7 arranged when energized to actuate the armature 8, which has a bifurcated portion 9 pivoted at 10 astride a projecting portion of the magnetic frame 6.

The armature 8 is shown as having rigidly secured to it, two horizontally disposed insulating rods or tubes 11 and 11' which serve as the supporting means for the movable members 12 and 12' of the two sets of contacts. These movable members are mounted on the brackets 13 and 13' pivoted in the bifurcated uprights 14 and 14' which are secured on the rods or tubes 11 and 11'.

The stationary members 15 and 15' of the two sets of contacts are mounted on the brackets 16 and 16' which are, in turn mounted on the back 5.

The members 15 and 15' are in conducting relation with the upper set of terminals 17 projecting rearwardly from the back 5, while the movable members 12 and 12' are arranged to be in conducting relation with the lower set of terminals 18 by means of the flexible conductors shown at 19 and 19' respectively.

The movable contact members 12 and 12' are arranged to be held in resilient engagement with the stationary members 15 and 15' and accordingly have springs 20 and 20' inserted between an overhanging portion of the pivoted brackets 13 and 13' and an abutment formed in the uprights 14 and 14'. 110

The motion of the brackets 13 and 13' is limited by means of the heels 21 and 21' which abut against portions of the uprights.

The springs 20 and 20' are compressed by 5 the closing movement of the contacts and consequently apply an acceleration in addition to gravity to the opening movement.

In order that part of this additional acceleration may be applied for an appreciable 10 interval of time after one set of these contact making members has opened I have advanced the closing point of the other set by inserting a liner or spacer 22 between the back 5 and its supporting bracket, here shown 15 as bracket 16. By this arrangement the two sets of contacts do not open simultaneously, but members 12' and 15' open first thereby allowing the resilient effect between the contacts 12 and 15 caused by the compression 20 of spring 20 to come into operation to apply acceleration to the opening movement for a sensible interval of time, after members 12' and 15' separate. That is, the compression of spring 20 is gradually relieved 25 until finally members 12 and 15 separate.

In order to assist in dissipating the arc, the first-opening set of contact-making members 12' and 15' are provided with a magnetic blow-out consisting of the coil 23 30 in series with these members and the arc chute 24 located between the pole pieces 25 of the coil 23.

The operation of this invention is as follows:

35 When it is desired to close the contactor the winding 7 is energized from the control circuit in the usual manner. The winding 7 accordingly attracts the armature 8 moving the members 12 and 12' to closed position. The member 12 first engages the member 15 by reason of its advanced position afforded by the spacer 22 and then members 12' and 15' engage.

The spring 20 is consequently more highly 45 compressed than spring 20' and applies an acceleration to the opening movement, when winding 7 is deenergized, after contact members 12' and 15' are separated until members 12 and 15 separate.

50 In practice the advancement of the closing point of one member by one eighth of an inch has served to increase the life of a contactor approximately 75 per cent.

As will be observed from Fig. 3, a multiple break in the electric circuit controlled 55 by the switch is effected; that is, the circuit in Fig. 3 is opened at two points. Although the switch does not open the two breaks in the circuit simultaneously, the opening of 60 the one break occurs a very short interval of time after the opening of the first break.

While I have here shown an embodiment 65 of my invention which is at present the best means known to me for carrying the same into effect, I would have it understood that

this is merely illustrative and that I do not mean to be limited thereby to the precise details here disclosed since obvious alterations thereof will appear to those skilled in this art, nor in the choice of recognized equivalents except as defined in my claims hereunto annexed.

What I claim as new and desire to secure by Letters Patent of the United States. is:—

1. An electromagnetic switch comprising 75 a plurality of pairs of simultaneously actuated relatively movable resiliently engaging contacts arranged to effect a multiple break in a circuit, the distance between one pair of contacts in the open position being 80 less than that between the remainder of the pairs of contacts, whereby the opening movement of said remainder of the pairs of contacts after their separation is accelerated 85 responsively to the resilient effect between said one pair of contacts.

2. An electromagnetic switch comprising 90 a plurality of pairs of simultaneously actuated relatively movable resiliently engaging contacts arranged to effect a multiple 95 break in a circuit, the distance separating one pair of contacts in the open position being less than the distance separating the remainder of the contacts, and means whereby the opening movement of said remainder of the pairs of contacts after their separation is accelerated 100 responsively to the resilient effect between said one pair of contacts.

3. An electromagnetic switch comprising 100 a plurality of pairs of simultaneously actuated relatively movable resiliently engaging contacts arranged to effect a multiple break in a circuit, the distance separating one pair of contacts in the open position being less than the distance separating the 105 remainder of the pairs of contacts, and means for advancing the closing point of said one pair of contacts whereby the opening movement of said remainder of the pairs of contacts after their separation is accelerated 110 responsively to the resilient effect between said one pair of contacts.

4. An electromagnetic switch comprising 115 a plurality of pairs of fixed and movable resiliently engaging contacts arranged to effect a multiple break in a circuit, means for simultaneously moving the movable contacts, a back, brackets thereon for supporting the fixed contacts at equal distances 120 from the movable contacts and a spacer for advancing one of the contacts of a pair toward its coöperating contact, so that in closing this pair of contacts first make engagement and the opening movement of another pair of contacts after their separation 125 is accelerated responsively to the resilient effect between said one pair.

5. In an electric switch, the combination 130 with an electromagnetic winding, of a pair of stationary contact members, a pair of

- movable contact members arranged to be simultaneously actuated by said winding to close a multiple break in a circuit, means for holding said members in resilient engagement when said movable members are in switch closed position; the distance between one pair of engaging members in the open position being less than that between the other pair, so that said resilient means still applies acceleration to the opening movement of the movable contacts after the other pair has opened.
6. In an electric switch, the combination with an electromagnetic winding, of a pair of stationary contact members, a pair of movable contact members arranged to be simultaneously actuated by said winding to close a multiple break in a circuit, means adapted to hold said members in resilient engagement when said movable members are in switch closed position; one pair of engaging members having their closing point advanced so that the distance between this pair in the open position is less than that between the other pair, whereby said resilient means still applies acceleration to the opening movement of the movable contacts after the other pair has opened.
7. In an electric switch, the combination with an electromagnetic winding, of a pair of stationary contact members, a back, a pair of brackets supporting said stationary members from said back, a pair of movable contact members arranged to be simultaneously actuated by said winding to close a multiple break in a circuit, a spring adapted to hold each of said movable members in resilient engagement with said stationary members when in switch closed position, one of said stationary contacts being advanced with reference to the other so that the spring associated with said one of said contacts still applies acceleration to the opening movement of said other pair of members after said other pair of members has opened.
8. In an electric switch, the combination with an electromagnetic winding, of a pair of movable contacts arranged to be simultaneously actuated by said winding, a pair of stationary contacts coöperating therewith, a back, a pair of brackets for supporting said stationary contacts at equal distances from the movable members, a spring adapted to hold each of said movable members in resilient engagement with said stationary contacts when the switch is in closed position; and a spacer located between the back and one of said contacts whereby the point at which the said contact is engaged by its movable contact is advanced, thereby enabling the spring, reacting against the movable contact in engagement therewith to apply acceleration to the opening movement of the movable contacts after the other pair of contact members has opened.
9. In an electric switch, the combination with an electromagnetic winding, of a pair of stationary contact members, a back, a pair of brackets supporting said stationary members from said back, an armature actuated by said winding, a pair of pivoted brackets arranged to be supported and moved simultaneously by said armature to effect a multiple break in a circuit, a spring arranged to react against each pivoted bracket and its armature support, contact members carried by each pivoted bracket and arranged to be held in resilient engagement with said stationary members when in switch closed position; one of said first named brackets being so mounted that the closing point of its pair of engaging members is advanced enabling its reacting spring to apply acceleration to the opening movement of said armature after the other pair has opened.

In witness whereof, I have hereunto set my hand this 7th day of Dec., 1917.

LEONARD P. HUTT.
